CLAIM

The ornamental design for a point of sale terminal as shown and described.

DESCRIPTION

FIG. 1 is a rear side perspective view of a point of sale terminal.

FIG. 2 is a front side perspective view of the point of sale terminal of FIG. 1.

FIG. 3 is a bottom side perspective view the point of sale terminal of FIG. 1.

FIG. 4 is a rear view of the point of sale terminal of FIG. 1. FIG. 5 is a front side perspective view of a point of sale terminal.

FIG. 6 is a side view of the point of sale terminal of FIG. 1. FIG. 7 is a side view of the point of sale terminal of FIG. 1. FIG. 8 is a front top perspective view of the point of sale terminal of FIG. 1; and,

FIG. 9 is a bottom view of the point of sale terminal of FIG. 1.

Aspects shown in broken lines are not considered to be part of the claimed ornamental design. The shading represents surfaces of the point of sale terminal only and forms no part of the claimed design.
